UNITED STATES PATENT OFFICE.

FRANK P. MOORE, OF EAST ST. LOUIS, ILLINOIS.

SEWING-MACHINE ATTACHMENT.

Application filed July 27, 1928. Serial No. 295,665.

The present invention relates to improvements in sewing machine attachments and has reference more particularly to a device for association with such machines as are used for sewing leather and like goods.

One of the important objects of the present invention is to provide a sewing machine attachment, whereby the work may be stitched with angularly disposed cross stitches, as well as facilitating the formation of straight stitches when the attachment is in an inoperative position.

A further object of the invention is to provide a sewing machine attachment of the above mentioned character which can be readily and easily mounted on a sewing machine without necessitating any alteration of the parts with which the invention is to be associated, the attachment at all times being positive and efficient in its operation.

Still a further object is to provide a sewing machine attachment of the above mentioned character which is simple in construction, inexpensive, strong and durable, and further well adapted to the purpose for which it is designed.

Other objects of the invention will become apparent as the description of the invention proceeds and when taken in connection with the accompanying drawings.

In the accompanying drawings, forming a part of this application and wherein like reference characters designate like parts throughout the several views:

Figure 1 is a fragmentary front elevation of the head portion of a sewing machine of the conventional construction, showing the position of my attachment with respect to the cross bar carried by the vertically movable presser foot bar, the attachment being disclosed in its inoperative position.

Figure 2 is an end elevation of the head structure of the sewing machine for more clearly illustrating the top of the attachment.

Figure 3 is a top plan view showing the manner in which the attachment engages over the cross bar.

Figure 4 is a detail perspective view of the attachment per se.

Figure 5 is a top plan view.

Figure 6 is a side elevation.

Figure 7 is a bottom plan view.

Figure 8 is a view similar to Figure 1, showing the position of the attachment when in an operative position.

Figure 9 is a fragmentary plan view of two pieces of material arranged edge to edge and formed with a zig-zag row of stitches such as may be produced by the attachment, one of the pieces being formed with a button-hole around which extends angularly disposed stitches, and

Figure 10 is a similar view of a piece of material having a circular formation of angular stitches produced by means of the attachment.

In the drawings, wherein for the purpose of illustration is shown the preferred embodiment of my invention, the numeral 1 designates the head of a sewing machine of a conventional construction, through which is movable the vertically disposed needle shaft 2, the needle carried by the lower end of said shaft being shown at 3. The needle 3 is adapted to pass through the usual presser foot 4, that is secured on the lower end of the vertically movable presser foot bar 5, and which extends through the head 1, and for the purpose of manually raising and lowering the presser foot bar 5, there is provided the usual lever 6, at the rear side of the head 1, in the manner also known in the art. The usual horn or platform of the sewing machine is shown at 7, and carried by this member is the work plate 8, that is located directly below the needle 3 and the presser foot 4.

At the upper end the needle shaft 2 is operatively associated with the forward end of the walking beam 9 that is located above the arm 10 that supports the head 1 in the usual manner.

Extending upwardly from the top of the head at the front side thereof is the rod like element 11 on which is disposed for rest upon the top of the head the plate 12 and these elements form a part of the thread tensioning means. A cross bar 13 is secured to the upper end of the vertically movable presser foot bar 5 for operation therewith and this cross bar extends transversely across the top of the head 1 and is formed at its forward end with an eye to accommodate the rod 11 and the spring urged sleeve 14, arranged on the upper end portion of the rod. The spring for normally urging the sleeve 14 downwardly is shown at 15.

My improved attachment is shown generally at 16 in Figure 4, and the same includes a single piece of metal that is so constructed as to include a circular base 17, formed with

a central opening 18 to accommodate the rod 11 and the outer edge of the base is flanged upwardly as shown.

An arm 19 extends upwardly from the outer edge of the circular base 17 at substantially right angles thereto and this arm gradually increases in width from its lower to its upper end.

A laterally disposed finger engaging lip 20 is formed at the upper end of the arm at the inner side edge portion thereof and this lip is disposed at substantially right angles with respect to the arm, as more clearly shown in the drawings, with reference more particularly to Figure 5.

Extending laterally from the inner side edge of the arm 19 in a direction opposite to the finger engaging lip 20 is the finger 21, the same being preferably located at a point below the lip 20 and the outer end of this finger terminates in a downwardly directed hook 22.

The attachment is positioned on the rod 11 in the manner as clearly illustrated in the drawings, and when the cross bar 13 is engaged by the laterally disposed finger 21, in the manner as shown in Figures 1, 2, and 3, the attachment is then in an inoperative position. In making straight stitches, the lever 6 is lowered, whereby the presser foot bar 5 and the presser foot 4 will be lowered.

When it is desired to form zig-zag or cross stitches, the neck 20 is engaged and actuated to swing the finger 21, off of the cross bar 13 and when the attachment is lowered, the member 17 will cooperate with the member 12 to tension the thread therebetween. The presser foot is not lowered when making the cross stitches. All that is necessary is to disengage the finger 21 from the cross bar and to lower the attachment that operates the sewing machine in the usual manner, so that two pieces of material may be stitched together in edge to edge relation by zig-zag stitching, as shown at 23, in Figure 9.

Furthermore, the material may be worked freely on the plate 8, either forwardly or rearwardly or laterally so that a circular patch 24 may be seated within the opening formed in the material 25, by the zig-zag stitching shown at 26, in Figure 10. A button-hole formed in a piece of material may have its edges reinforced by zig-zag stitching as shown at 27, in Figure 9.

When it is desired to make straight stitches the hand lever 6 is lowered and the sewing machine operated in the ordinary manner.

It will thus be seen from the foregoing description that I have provided a sewing machine attachment that will permit the formation of zig-zag or cross stitches as well as straight stitches, and the attachment is of such construction as to enable the same to be mounted upon a conventional sewing machine without necessitating any alteration of the

parts of the machine with which the attachment cooperates.

An attachment of the above mentioned character will furthermore be positive and efficient in its operation and due to its simplicity can be constructed and sold at a very low cost.

While I have shown the preferred embodiment of my invention, it is to be understood that various changes in the size, shape and arrangement of parts may be resorted to, without departing from the spirit of the invention or the scope of the appended claims.

What I claim is:

1. A sewing machine attachment comprising a thread tensioning base provided with an opening to accommodate the rod that extends from the top of the head of the sewing machine, an arm extending upwardly from the outer edge portion of the base, a finger engaging portion formed on the upper end of the arm to facilitate raising and lowering, as well as the turning of the thread tensioning base, and means carried by the arm for engagement over the cross bar that is carried by the upper end of the vertically movable presser foot bar for maintaining the tensioning base member in an inoperative position.

2. A sewing machine attachment comprising a thread tensioning base provided with an opening to accommodate the rod that extends from the top of the head of the sewing machine, an arm extending upwardly from the outer edge portion of the base, a finger engaging portion formed on the upper end of the arm to facilitate raising and lowering, as well as the turning of the thread tensioning base, and means carried by the arm for engagement over the cross bar that is carried by the upper end of the vertically movable pressure foot bar for maintaining the tensioning base member in an inoperative position, said last mentioned means comprising a finger extending laterally from the intermediate portion of said arm.

3. A sewing machine attachment comprising a thread tensioning circular base adapted for disposition over a rod that projects upwardly from the top of the head of a sewing machine, the thread being tensioned between said base and the top of the head when the base is in a lowered position, an arm extending upwardly from the outer edge portion of the base, a finger engaging lip extending laterally from the upper portion of the arm, and a finger extending laterally from the intermediate portion of the arm in the opposite direction with respect to the lip for detachable engagement over the cross bar carried by the upper end of the vertically movable presser foot bar for holding the attachment in an inoperative position.

In testimony whereof I affix my signature.

FRANK P. MOORE.
